UNITED STATES PATENT OFFICE.

ROCKWELL SAYRE, OF CHICAGO, ILLINOIS.

DESIGN FOR A BOTTLE.

Application filed May 15, 1922. Serial No. 2,239. Term of patent 14 years.

To all whom it may concern:

Be it known that I, ROCKWELL SAYRE, a citizen of the United States, a resident of Chicago, county of Cook, and State of Illinois, with a post-office address at 104 E. 51st St., Chicago, Illinois, have invented a new, original, and ornamental Design for Bottles, of which the following is a specification, reference being had to the accompanying drawing, forming part thereof.

I claim:

The ornamental design for a bottle as shown.

ROCKWELL SAYRE.
